[57] CLAIM

The ornamental design for a ground working tool, as
shown and described.

DESCRIPTION

FIG. 1 is a top, rear, right side perspective view of a
ground working tool, showing my new design;
FIG. 2 is a rear elevational view thereof;
FIG. 3 is a front elevational view thereof;
FIG. 4 is a right side elevational view thereof, the left
side being a mirror image thereof;
FIG. 5 is a top plan view thereof; and,
FIG. 6 is a bottom plan view thereof.
